UNITED STATES PATENT OFFICE

2,426,718

HEAT-TREATING APPARATUS

Otto J. Vanek, Cleveland, Ohio, assignor to The American Steel and Wire Company of New Jersey, a corporation of New Jersey

Application April 2, 1945, Serial No. 586,191

5 Claims. (Cl. 263—6)

1

This invention relates to improved heat treating apparatus of the type wherein metal articles are heated and quenched.

The invention has among its objects the provision of heat treating apparatus wherein a batch of metal articles is so treated that the structure thereof is uniform both throughout each article and from article to article.

A further object of the invention is the provision of such apparatus in which the time from the cessation of the heating operation to the delivery of the articles into the quenching bath is markedly reduced.

A still further object of the invention is the provision of heat treating apparatus wherein the transfer of the heated articles from the heating zone to the quenching zone is rapidly and easily accomplished.

These and other objects of invention will be more apparent in the following description.

In the heat treating of articles, particularly batches of elongated articles such as bars and the like, where such treatment involves the heating and subsequent quenching of a plurality of articles at one time, it has been customary to heat such articles in either a box type or a car-bottom furnace with the article supported on a rack, to remove the box type furnace cover or to run the car out of the furnace, and then to pick up the rack with the articles thereon as by a crane and either to lower the rack with the stock thereon into the quenching bath or to tip the rack so as to cause the articles to fall therefrom into the quenching bath. The time required to accomplish such manipulation of the stock support, after removal of the furnace therefrom or its removal from the furnace, allows the heated articles to cool materially before quenching, particularly on their outer surfaces, so that the resultant heat treated articles frequently do not have the desired structure or hardness. Furthermore, because of the non-uniformity of such cooling throughout the batch, the heat treated articles vary considerably from article to article; a great many of them treated in such manner have to be scrapped or at least recharged again into the furnace for reheating and re-quenching, thereby causing a material increase in cost for the particular heat treating operation involved.

The apparatus of the present invention overcomes the difficulties, outlined above, attendant upon the use of prior art apparatus, by providing a stock or article support which may be tilted immediately after removal of the furnace therefrom

2

or removal of the stock support from the furnace. Tilting of the stock support, which may, when a box type furnace is employed, be accomplished as an incident to the lifting of such furnace, allows the articles to be discharged by gravity and to fall into an appropriate quenching tank. The apparatus of the present invention also provides novel skids or guides between the stock support or rack and the quenching tank to guide the heated articles discharged from the support into the quenching tank.

The invention will be more readily understood by reference to the accompanying drawings, in which:

15 Figure 1 is a view in vertical section through heat treating apparatus of one modification of the invention in which a box type furnace is employed;

Figure 2 is a view in vertical cross section of 20 the apparatus shown in Figure 1 with the furnace cover lifted from the article supporting rack;

Figure 3 is a view in cross section showing details of the stock supporting rack and the operating skid members, said section being taken on line III—III in Figure 2;

Figure 4 is a view in plan of another modification of the heat treating apparatus of the present invention, in which a car-bottom type furnace is employed; and

Figure 5 is an end view of the apparatus shown in Figure 4.

In the modification of the apparatus shown in Figures 1, 2, and 3, the elongated box type furnace 2, which may be of a type similar to that shown in the patent to Woodson, No. 2,068,477, is adapted to be lifted by means of a crane to allow the charging of the material thereinto and the discharge of the heated material therefrom.

40 Furnace 2 when in operative position, as shown in Figure 1, rests upon a furnace base 4, which in this instance, is positioned between and equidistant from two quenching tanks 6 and 8, which are made of a suitable length to receive the articles being treated. Tank 6 may, for instance,

contain a bath of oil which may be used in the heat treatment of one particular type of steel, whereas tank 8 may contain water which may be used in the heat treatment of different types of steel or in a different type of heat treatment of the same kind of steel. In Figures 1, 2, and 3 the articles to be heat treated are shown as receiving an oil quenching; consequently, tank 8 is not used in such method and is shown with

65 its cover down.

Positioned on top of furnace base 4 are a plurality of rack supporting members 10 which may be, for instance, in the form of hollow U-shaped beams extending in the direction at right angles to the paper for the length of the stock supporting rack 12, on top of which is positioned the charge 13 which in this instance consists of a plurality of elongated bars. The charge supporting rack is made up, as shown in Figures 1 and 3, of a plurality of spaced cross beams 14 held together by a plurality of inter-fitting diaphragm beams 16 welded thereto, said rack being provided on the top thereof with an article supporting plate 18 welded to the frame.

To allow the tilting of the stock supporting rack in the direction of the quenching tank which is to be used, said rack is provided at one bottom edge thereof with a longitudinal pivot bar 20 which seats in one set of a plurality of yokes 22, situated on the edge of the support 10. When but one quenching tank is employed, it is obviously necessary to provide only one set of yokes 22 on the edge of support 10 adjacent the tank. In the modification shown in Figures 1 and 2, however, yokes 22 are shown provided on both edges of support 10 so that the rack may be reversed in position merely by being picked up by a crane and turned around, and thus may be made to cooperate with either quenching tank.

Positioned on the upper edge of the rack 12, 30 at a position opposite the pivot bar, is a rack lifting bar 24 by which the rack may be tilted, in a manner subsequently described; another longitudinally extending bar 26 is provided on the edge of the rack at a position somewhat 35 below the top 18 of the rack and on the same side thereof of the pivot bar 20. Bar 26 is provided for the support of the article guiding skids 36 over which the articles travel into the quenching tank. The bottom outer edge of the box 40 type furnace 2 on the side opposite the quenching tank being used is provided as shown with a hook 28 which may be attached thereto as by a short chain. Hook 28 is provided with a long handle 30 so that the hook may be manipulated at a distance so as to be engaged with lifting bar 24 when the furnace is raised.

The quenching tank 6 is provided with a cover 32 connected thereto by a hinge 34 on the edge thereof adjacent the furnace so that the cover may be swung into a position inclined toward the furnace as shown in Figure 1. The outer end of the cover is provided with a plurality of skids or arms 36 hinged thereto at 38 so that the arms may be swung outwardly into a plane coextensive with the cover. The arms may be held in such coextensive position by means of U-bolts 40 embracing the arms and extending through the outer edge of the cover.

The other quenching tank 8, which is shown in Figures 1 and 2, is likewise provided with a cover 32' hinged thereto at 38', said cover having skids or arms 36' pivoted thereto. When either quenching tank is not being used, the U-bolts 40 are removed so as to allow the skids or arms to hang freely from the cover, as shown in connection with quenching tank 8, when the cover is positioned over the tank.

The apparatus shown in Figures 1, 2, and 3 may be employed in the heat treatment of a batch 70 of articles, for instance, a plurality of elongated bars, in the following manner. The stock supporting rack 12, in a horizontal position as shown in Figure 1, receives the charge of articles thereon with the furnace 2 hoisted from furnace base 75

4. The furnace is then lowered into operative position on the base and is operated to bring the charge to the desired temperature. The cover 32 of the quenching tank 6, with the arms 36 held in rigid extended position thereon, is then tilted so that the outer ends of the arms contact the side of the furnace as shown in Figure 1. When the articles have been heated to the desired temperature, the furnace heating means is shut off and the furnace is hoisted, as by means of the crane hook 44, to raise it clear of the furnace base for the discharge of the articles. During such hoisting, the furnace is caused to travel somewhat to the left of the furnace base as shown in Figure 1 to bring hook 28 into such position relative to lifting bar 24 that it may engage the bar when manipulated by handle 30. At such time, the furnace will have been lifted sufficiently to allow the outer ends of the arms 36 to clear the bottom edge of the furnace and thus to allow the cover 32 and the arms 36 as a whole to drop until the arms rest upon bar 26. In such position the top surfaces of the arms 36 lie slightly beneath the top surface of the article supporting plate 18 of the rack so that upon further lifting of the furnace and consequent tilting of the rack, the heated articles roll or slide off the rack onto the arms thence to the cover of the tank and into the tank. The tilting of the article supporting rack and the discharge of the articles thereon in a manner described may be accomplished in a very short time, so short in fact that little or no cooling of the articles takes place before they drop into the quenching bath. Consequently, the articles may be heated to the optimum temperature, and uniformity heat treatment in the individual articles throughout their extent as well as uniformity from article to article in the batch will be insured.

Although the modification of the apparatus of the present invention shown in Figures 1, 2, and 3 displays perhaps the most advantages as far as speed and simplicity of operation are concerned, the apparatus is also capable of use and displays advantages in connection with heating furnaces other than those of the box type. One such other type of furnace is that shown in the modification illustrated in Figures 4 and 5. In this modification the tilting stock supporting rack and the cooperating quenching tank having a pivoted cover and extension arms or skids are employed with a furnace of the car-bottom type. Such furnace, which is shown at 46 is provided with a vertical sliding door 48 which covers an opening in the end of the furnace into which the car 50, supported on tracks 52, may travel. Quenching tank 54 is located at a position alongside tracks 52 so that the articles supported on the car may be discharged into the tank when the car is retracted from the furnace as shown in Figure 4. The quenching tank 54, which is of the length sufficient to accommodate the articles being treated is similar to the tanks 6 and 8 in the first modification above described. Tank 54 is provided with a hinged cover 53, said cover having a plurality of extension or skid forming arms 58 pivoted and secured thereto in the same manner as in the first modification. The charge supporting rack 60, which is supported on supporting member 62 on top of the car 50, is provided at the bottom edge thereof adjacent tank 54 with a longitudinal pivot bar 66 resting in a plurality of yoke members 64. Rack 60 is likewise provided with a longitudinally extending bar 68 for supporting the outer ends of arms 58, and with a

rack lifting bar 70 on the side thereof opposite the pivot bar 66.

In the apparatus shown in Figures 4 and 5, the articles to be heat treated, which may be a plurality of bars 61, are loaded upon the rack 60 with the car in its outer position, and the car is then run into the furnace where it remains until the charge has reached the desired temperature. Thereupon the car is retracted from the furnace and the cover 56 of the quenching tank with the arms 58 in extended position is then swung to a position so as the arms rest upon skid supporting bar 68. Lifting bar 70 is then engaged with a suitable lifting means, and the supporting rack is then tilted into a position such that the charge of bars rolls down the racks onto the skid arms 58, to cover 56, and into the quenching tank. The lifting means for accomplishing tilting of the rack is shown in Figure 5 as consisting of a hook 72 attached to a crane cable 76, said hook having a long handle 74 affixed thereto to allow an operator to engage the hook with lifting bar 70 at a distance. Such operations may easily and rapidly be carried out so that only a very small time elapses from the withdrawal of the charge from the furnace until it has been discharged into the quenching tank. Consequently, this modification of the apparatus as well as the first allows the production of heat treated articles which are characterized by their uniformity of heat treatment throughout their extent as well as uniformity of structure from article to article in the batch.

Although I have described and illustrated herein preferred forms of construction of the heat treating apparatus of my invention, it will be obvious that changes in the constructions shown may be made without departing from the spirit of the invention or the scope of the appended claims.

I claim:

1. Apparatus for heat treating a batch of elongated metal articles comprising a furnace to receive such articles, an elongated article holding rack supported normally in horizontal position in the furnace, the support for the rack comprising a horizontal pivot parallel to the length of the rack about which the rack may be tilted to discharge heated articles sidewise therefrom, means to tilt the rack, a quenching tank located adjacent the furnace with its dimension parallel to the length of the rack great enough to receive the elongated articles, and movable skid means which may be selectively interposed between the tank and the rack to convey the heated articles from the rack, when the latter is tilted, into the tank.

2. Apparatus for heat treating a batch of elongated metal articles as defined in claim 1, in which the skid means comprises a cover for the quenching tank, said cover being hinged to the

upper edge of the quenching tank adjacent the furnace, said cover being swung on its hinge to lie in a direction toward the rack when functioning as an article conveying skid.

3. Apparatus for heat treating a batch of elongated metal articles as defined in claim 1, in which the rack is provided with a skid rest on the side thereof confronting the quenching tank, and in which the skid means comprises a cover for the quenching tank and extension arms thereon, said cover being hinged to the upper edge of the quenching tank adjacent the furnace, said cover being swung on its hinge to lie in a direction toward the rack when functioning as an article conveying skid, the extension arms on the cover being supported at their outer ends by the skid rest on the rack when the skid is in article conveying position.

4. Apparatus for heat treating a batch of elongated metal articles comprising a box type furnace adapted to be raised to allow the charging of material into it and the discharge of material from it, an elongated article holding rack normally supported in the furnace in horizontal position, the support for the rack comprising a horizontal pivot parallel to the length of the rack about which the rack may be tilted to discharge heated articles sidewise therefrom, means to raise the furnace clear of the rack, and means connected to the furnace to tilt the rack as the furnace is raised.

5. Apparatus for heat treating a batch of elongated metal articles comprising a box type furnace adapted to be raised to allow the charging of material into it and the discharge of material from it, an elongated article holding rack normally supported in the furnace in horizontal position, the support for the rack comprising a horizontal pivot parallel to the length of the rack about which the rack may be tilted to discharge heated articles sidewise therefrom, said pivot being located in the vicinity of one lower longitudinal edge of the rack, means to raise the furnace clear of the rack, and means connected to the furnace which may be connected to the rack on the side thereof opposite the pivot for tilting the rack as the furnace is raised.

OTTO J. VANEK.
